TENS-CARRY MECHANISM

Oluf L. Cleven, Washington, D. C.

Original application July 28, 1939, Serial No. 286,976. Divided and this application December 20, 1939, Serial No. 316,132

8 Claims. (Cl. 235—137)

(Granted under the act of March 3, 1883, as amended April 30, 1928; 379 O. G. 757)

This invention relates to tens-carry mechanism for tabulating machines or other machines in which such mechanism is required or desired.

The invention, if patented, may be manufactured and used by or for the Government of the United States for governmental purposes without the payment to me of any royalty thereon, in accordance with the provisions of the act of April 30, 1928 (ch. 460, 45 Stat. L. 467).

This application is a division of my application Serial No. 286,976, filed July 28, 1939, for Tabulating machines. So much of the illustrations of the present case are taken from the former application as are deemed necessary to illustrate the tens-carry mechanism in connection with the mechanisms with which it is associated in said application.

The object of the invention is to simplify the tens-carry or transfer mechanism by combining the carry and print controls, thereby eliminating costly and trouble-making machinery, and to effect the tens-carry of all of the accumulator wheels that are ready for tens-carry, simultaneously instead of progressively.

In the drawings illustrating the invention—

Figure 1 is a sectional view taken about through the center of the rear portion of a tabulating machine, showing a sensing means, the accumulators, the tens-carry mechanism, and a printing mechanism.

Figures 2 to 6 are fragmentary views of the transfer or tens-carry mechanism showing several different and progressive positions of the accumulator wheels and associated tens-carry parts.

Figures 7 to 10 are detail fragmentary top edge views of the tens-carry levers showing the various positions of certain pins and cams carried by said levers, and,

Figure 11 is a detail view of the reset mechanism showing the zero position of the accumulator wheels and associated parts.

Figure 12 is a detail view of the pivoted bail-carrying member for resetting the print levers after a printing operation.

The various parts of the mechanism about to be described will be indicated by the same reference characters as are employed in the parent case, so that this divisional patent, if and when issued, may be more readily connected with the parent case.

Referring to the drawings, and particularly to Figure 1, the numeral 1 designates the main driving shaft of the tabulating machine to which the tens-carry mechanism about to be described is particularly appropriate. This shaft carries the large gear 2 shown in dot-and-dash lines. The ratio of the gear to other gears and parts is such that it represents, with one revolution, four card feed cycles. This shaft, as well as many of the

associated parts, is mounted in side plates A. The top of the machine is formed by a deck comprising parts 33, 33' and 33'', over which the cards pass from the feed hopper (not shown) between the feed rolls 6 and 10 to and between the sensing roll 53 and feed rolls mounted just below the sensing roll, and from thence over deck portion 33'' to the open upper end of the card chute 29. At each open side of the chute there are arranged a suitable number of feed rolls that feed the cards to a stacking hopper (not shown).

Below the spring-backed sensing roll 53 and extending through an opening in the deck portion 33' is the enlarged end 11 of release lever 14, pivoted at 75 between ears 76, there being a plurality of these ears and also a plurality of release levers corresponding to the number of columns on the card to be tabulated. The rear ends of these levers are broadened as indicated at 77 and are engaged and rocked on their pivots 75 by spring-backed sensing fingers 63 of sensing roll 53 when the hole in the record or card is sensed. The forward ends 79 of the levers are arranged to engage the narrowed ends 80 of the accumulator arms 81, there being an arm for each accumulator and for each release lever.

The lower ends of the arms 81 are pivotally mounted on shaft 182, mounted in the side plates B, which plates are within the outer side plates A, the construction preferably being such that the whole unit containing the tens-carry and accumulator mechanism may be bodily removed from between the plates A.

Loosely mounted on a stud on the accumulator arm 81 is a pinion 84', there being a pinion for each arm and each accumulator wheel 84. These accumulator wheels are loosely mounted on the shaft 82 and are constantly in mesh with said pinions, and when the release lever 14 releases the arms 81 the pinion of the actuated arm will be caused to mesh with the elongated actuator gear 86 which is mounted on shaft 87 in the inner side plates B. Each accumulator wheel has rigidly secured thereto a step read-out member 85, which comprises 4 similar arms each having ten steps which function solely in the printing operation. On the extreme end of each arm of the read-out member is a cam point 102, which points are arranged to engage a two-point cam 103, one of which is carried on the upper edge of each print and tens-carry lever 104. These levers are each provided at their rear ends with an elongated slot 106 which embraces the long rod 107 extending between the inner side plates A and upon which the levers are supported at their rear ends. These levers are otherwise supported at their front ends by springs 111 which are attached to a pawl 112, one of which is pivotally mounted at 113 on each lever, and each pawl has a point for engagement with the teeth

of the accumulator wheel of the next higher order, there being a pin 196 on each lever for engagement with the pawl to limit its upward movement under the influence of spring 111. The front end of lever 104 is cut away to form a shoulder 108 and a narrow extension 109 which terminates in a downwardly extending hook 114, the purpose of which will presently appear.

A bar 110 spans the distance between the two inner side plates B and forms a stop for the forward ends of levers 104 until they are moved down and off the bar by the cam point 102 of the step read-out member 85, and urged forward by the spring 111 until its hook 114 momentarily rests in groove 115 formed in the forward end of a plate 116 pivoted at 117 to the lower ends of levers 118. There are two of these levers, one at each side of the machine, which are pivoted at 119 on studs 120 on the inner sides of the side plates A. Each of said levers carries a roller 121 held in constant engagement by spring 123 with the periphery of cams 122, one on each side of the machine, and fast to shaft 1. There is a spring 124 which is preferably just sufficiently strong to support the weight of the plate 116 and to hold it in its working position, which is mainly in a horizontal direction.

There is a pin 126 (Figures 2 to 10) on each transfer lever 104 near its forward end and which cooperates with a cam 127 carried by the next higher value or adjoining lever throughout the machine; or in other words, each lever is provided with a pin on one side and a cam on the other.

The levers 118 are actuated against the tension of springs 123, by the cam 122 on shaft 1. This cam is formed with four high-points 125 corresponding to the four card feed cycles of the machine. The tens-carry mechanism operates between cards, and the cams 122 are so shaped as to provide suitable depressions which when engaged by rollers 121, permit the levers 118 to rock forward under the influence of springs 123. Between every card the levers 118 and the plate 116 carried thereby will be rocked, whether there is a tens-carry operation or not, but when there is a tens-carry, which is at the time that cam point 102 has passed the high point 103 of the two-point cam, and depressed the forward end of the lever 104 and cleared it of the stop 110, when hook 114 of said lever will rest momentarily in the groove 115 of plate 116, as clearly shown in Figure 2. On the further movement of cam 122, as shown in Figure 3, the lever 104 will be carried further forward by reason of its engagement with the plate 116. Upon a still further movement of the cam 122, as shown in Figure 4, and when the high-point 125 is in engagement with roller 121, the lever 118 and its plate 116 will bring back the lever 104, and in doing so the pawl 112 on the lever will engage a tooth on the adjoining accumulator wheel of the next higher order and advance this wheel the distance of one digit, and also cause lever 104 to be restored to the position shown in Figure 4 against the stop bar 110.

In tens-carry mechanisms of machines of this character, whenever a number is added to "9" it must affect the next higher value accumulator wheel and thus carry one to this next higher wheel. For instance, one of the accumulator assemblies may have reached such a position as to represent a series of the numeral "9," as shown in Figure 1, wherein it is intended to show that several of the step read-out members 85 are side by side in exactly the same position and all

registering "9," in which position the cam points 102 have engaged the forward step of the two-step cam 103 and brought the lever half-way down on the stop bar 110, as shown in said figure. 5 Now, as the wheel of the lower order passes from this "9" position, the tens-carry lever 104 is depressed and clears the stop bar 110 where this tens-carry lever is in position to carry one to the next higher accumulator wheel, and in doing so 10 the pin 126 (Figure 5) will slide over the cam 127 on the next higher order transfer lever and disengage said lever from the stop bar 110, and in 15 effecting this disengagement this lever in turn will operate upon the next higher order transfer lever in the same manner and so on until the tens-carry operation has been effected in the successive higher order wheels as required and as progressively illustrated in Figures 4, 5 and 6, and in plan positions in Figures 7, 8, 9 and 10. When 20 the accumulator wheel stands in any other position than the "9" position the pin 126 passes under the cam 127 and in no way disturbs the adjacent lever.

Referring to Figure 2, the lower order accumulator wheel 84 has passed to "0" position and in 25 doing so engages the point 103 of its associated lever 104, and depresses said lever to a point below the stop bar 110, as shown. Meanwhile the shaded lever 104 with its associate accumulator wheel 84 is standing on "8" and in the position shown in this figure. Upon further movement of the cam 122, as shown in Figure 3, and between card sensing cycles the lever 104 under the influence of spring 111 will move forward and allow 30 the pin 126 to pass under the cam 127 of the shaded lever 104 or next higher order lever, which operation is shown clearly in Figures 7 and 8. On still further movement of the cam 122, as 35 shown in Figure 4, upon the rearward movement of lever 118, the lever 104 is brought back to stop 110 and while moving back to this position the pawl 112 engages the next higher order accumulator wheel 84 and advances this wheel one step.

Referring to Figure 5, the step read-out cam 85 40 associated with the front lever has passed from "9" to "0." The next higher order read-out cam is standing on "9" on its associated lever 104, which lever is partly depressed as shown. In the position of the cam 122, as shown in Figure 3, it 45 has allowed the lever 118 to be rocked forward under the influence of spring 123 and has allowed lever 104 to move forward also, and as shown in Figure 6, allowed the pin 126 on lever 104 to engage cam 127 on adjacent lever of higher order 50 and exert a camming action between said cam and pin, thereby depressing the lever to a point below the stop bar 110. This operation is further 55 illustrated in Figures 9 and 10, wherein, in the former or Figure 9, the pin 126 is shown about to engage the cam. In Figure 10 the pin has 60 reached a point where the next higher order lever has been depressed and brought to position shown in dotted lines in Figure 6, in which position the lever 104 is free to move forward as heretofore 65 described. While all levers which have been acted on by a tens-carry operation are being reset back on stop bar 110, each lever with its pawl 112 will advance its adjacent accumulator wheel 70 of higher order one step, thus carrying one to the next higher order wheel.

So far, the functions of the levers 104 have been explained in connection with the transfer or tens-carry operation. However, these levers also function importantly in the operation of printing 75 the results of the tabulation, and to accomplish

this, each lever is provided near its rear end with a finger 151 arranged to engage one or another of the steps on the arms of the step read-out members 85. To start the printing operation the conventional single revolution clutch shown in my application Serial Number 286,976 is released, causing shaft 128 to make one revolution. The first movement of the shaft will bring down bail 149.

When the forward ends of such of the levers 104 as have been actuated are in the path of the downward movement of the bail 149 (Figures 1 and 11) which extends over all of the lever extensions 109, they will be released from the stop 110 by the bail, and, under the influence of springs 111 (there being a spring for each bar), will be brought forward causing the finger 151 of such bars as have been actuated to engage the step on the read-out member 85 appropriate to the amount stored on the accumulator wheel associated with the particular actuated bar.

As clearly shown in Figure 1, the rear ends of the levers 104 engage one or another of the steps 154 of the step read-out bars 153, corresponding to the amount represented by the particular step. These step read-out bars are held normally in their lowermost position by bail 161 that connects the rear ends of two pivoted bars 158 pivoted at 158' on the inner side plates B. Each arm 158 is formed with a forwardly-extending upwardly-inclined arm 159 (Figure 1), each provided with a roller 160 constantly in engagement with cam 145 fast on shaft 128. There are two of these cams, one on each side of the machine. The step read-out bars 153 are each provided with lateral extensions 156 upon which the bail 161 normally rests, keeping all of the bars normally in their lowermost or reset position against the tension of springs 157 which are attached to said extension and to a cross-bar 156' near the top of the machine.

As explained, the first movement of the cam 145 is to bring down bail 149 for engagement with the forward ends of all of the print and tens-carry levers 104 that have been actuated and at this time the fingers 151 will find their appropriate steps of the step read-out members 85. A further movement of the cam 145 will allow the rollers 160 to drop into the low portion of the cam thereby permitting the springs 157 to rock the arms 158 positioning the bail 161 to allow the step read-out bars to find their appropriate position with respect to the location of the print and tens-carry levers 104. Any of the step read-out bars 153 that have been positioned by actuation of the levers 104 will be raised according to the value of the step occupied by the rear ends of said bars, and the bars in moving up will engage the swinging pendants 178 pivoted to printing sectors 172, there being a swinging pendant for each sector, and each step read-out bar. These sectors are loosely mounted on a rod 173 connecting the ends of short links 174 pivoted on studs 175, one of which is provided on each side plate A. The sectors, each having printing characters thereon, are raised by the bars through links 178 according to the amounts represented by the steps on said bars, bringing the characters in position to make an impression on the result sheet interposed between said sectors and a suitable platen 177, it being understood there will be a suitable inked ribbon between the paper or result sheet and the platen.

The numeral 169 (Figure 1) represents print levers of which there are two, one at each side 75

of the machine rockably mounted on studs 170 on the side plates A. The upper ends of these levers are connected by a push bar 171 which extends crosswise of the machine through the 5 openings in the sectors 172 and in position to engage one or another of the notches 180 of said sectors when the bars are rocked through the movement of links 168 pivoted to the lower ends of print levers 169, as fully described and 10 illustrated in my application herein referred to and of which this application is a division.

In the position of the parts described the mechanism is conditioned for a printing operation. After this takes place, all the parts are 15 reset to their normal position. There is a cam 181 on shaft 128 and in the further movement of this shaft and cam the step read-out bars 153 were reset by cam 145 and after that the high point 196' of cam 181 engages a roller 184 mounted on a spindle 184' on pivoted member 182 which member carries a bail 186 which encompasses all of the bars 104 and rocks the said member and bail rearward into engagement with the ends of all of the levers 104 that have been actuated, thereby resetting them to their normal position with their shoulders 108 against the high point 110' (Figure 11) of step 110, which position is the first position after the machine is entirely reset.

30 The member 182 is centrally located in the machine and is pivoted at 183 to a suitable support. It is bifurcated for the passage of the bar 185 which is pivoted at its forward end at 183' to an ear 182' integral with said member and has in its rear end an opening for the passage of a stud 185' on the lower end of lever 187. This lever is fastened on a rod 188 mounted in the side plates B. Near each end of this rod is rigidly attached a bent lever 189 (Figure 11) in the upper end of each of which is pivoted a comb holder 191. These holders carry a comb 192 that extends substantially for the entire width of the machine, there being a comb tooth for each step read-out member 85 and accordingly, 45 for each accumulator wheel. Each comb holder 191 carries a roller 193 which works in angular cam slot 194 formed in each of two plates 195, one of which is secured to each side plate B. Upon the still further movement of cam 181 and the rocking of the bracket 182 the shaft 188 will be rocked and the bent levers 189 will also be rocked forward and will bring a tooth of the comb 192 into contact with the under side of any arm of the step read-out member 85 50 that is not standing in reset position and reset said members and their associated accumulator wheels to zero position, or that position shown in Figure 11.

Between each card cycle, the accumulator 60 mechanism is reset to its normal position or that in which all of the accumulator arms 81 are in the position shown in Figure 1, wherein their upper ends 80 are latched against the ends of the release levers 74. After the accumulator 65 wheels have been actuated, it is necessary to reset all of the accumulator arms 81 and for this purpose cams 90 (one on each side of the machine and shown in shaded lines in Figure 1) are provided and are rigidly mounted on shaft 1. These cams cooperate with levers 91, also shown in Figure 1, which are pivotally mounted on studs on the side plates A, there being one of these levers mounted on each side of the machine. These levers carry a roller 92 in constant engagement with the cam 90 and held in 70

such engagement by springs 93. The upper ends of the levers at each side of the machine are pivotally connected with resetting arms 94 whose rear ends are connected by a bail 95 extending across all of the actuating arms 81, the bail being arranged to engage and reset all of the arms 81 when the rollers 92 engage the high points 96 of cams 90, between each card feed cycle.

I claim:

1. In a machine of the character described, in combination, accumulator wheels of lower and higher order, a tens-carry element carried by the lower order wheel, a lever capable of a joint reciprocating and pivotal movement for the lower order wheel, means common to all of said levers for maintaining the lever in normal position, means carried by said lever and cooperating with the tens-carry element of the accumulator wheel to disengage said lever from its maintaining means to condition it for tens-carry on the next higher order wheel, means carried by the lever for actuating the next higher order accumulator wheel as said lever is restored to normal position, and means for moving said lever to normal position to effect a tens-carry.

2. In a machine of the character described, in combination, accumulator wheels, a tens-carry element carried by each wheel, a transfer lever capable of a joint reciprocating and pivotal movement for each wheel, a stop common to all the levers for holding them in normal position, means for urging the levers against the stop, a two-step cam carried by each lever for engagement with the tens-carry element of each lower order wheel, one step of said cam being positioned to be first engaged by the tens-carry element when passing from "8" to "9" whereby the levers are partially disengaged from the stop, additional means carried by the levers comprising a cam on one side and a stud on the other for engaging the cam on the lever for the next higher order wheel for wholly disengaging said levers upon the movement of the lower order lever when said lever is released by the tens-carry element passing beyond the second step of the two-step cam in passing from "9" to "0," and means carried by each lever for actuating the higher order accumulator wheel as said lever is restored to normal position, and means for moving the levers to normal position to effect a tens-carry.

3. Tens-carry mechanism for accumulator apparatus including registering elements of lower and higher order, a reciprocable transfer lever capable of a joint reciprocating and pivotal movement for each lower order registering element, a carry pawl mounted on each lever and cooperating with the next higher order registering element, a stop for each lever common to all of said levers for maintaining them in normal position, means for releasing the levers from the stops, and positive means for restoring said levers to effect a tens-carry.

4. Tens-carry mechanism for accumulator apparatus including registering elements of lower and higher order, a reciprocable transfer lever capable of a joint reciprocating and pivotal movement for each lower order registering element, a carry pawl mounted on each lever and cooperating with the next higher order registering element, a stop for the levers common to all of said levers for maintaining them in normal position, means for releasing the levers

from their stops, a tens-carry element for each lower order element, a cam carried by each lever cooperating with the tens-carry element for releasing the levers from their stops, and positive means for restoring said levers to effect a tens-carry.

5. Tens-carry mechanism for accumulator apparatus including registering elements of lower and higher order, a transfer lever capable of a joint reciprocating and pivotal movement for each lower order registering element, means carried by each lever and cooperating with the next higher order registering element, a stop for each lever common to all of said levers for maintaining them in normal position, a two-step cam carried by each lever, a tens-carry element carried by each lower order registering element for engagement with the first step of said cam to partially release the levers from their stops in passing from "8" to "9" thereby positioning the levers for a carry-on-a-carry.

6. Tens-carry mechanism for accumulator apparatus including registering elements of lower and higher order, a reciprocable transfer lever capable of joint reciprocating and pivotal movement for each lower order registering element, means carried by each lever and cooperating with the next higher order element, a stop for each lever common to all of said levers for maintaining them in normal position, a two-step cam carried by each lever, a tens-carry element carried by each lower order registering element for engagement with the first step of said cam to partially release the levers from their stops in passing from "8" to "9" and additional means carried by the levers for wholly releasing the higher order levers from their stops when the lower order lever is released by its tens-carry element passing beyond the second step on said two-step cam to effect a carry-on-a-carry.

7. Tens-carry mechanism for accumulator apparatus including registering elements of lower and higher order, a transfer lever capable of joint reciprocating and pivotal movement for each lower order registering element, means carried by each lever and cooperating with the next higher order element, a stop for each lever for maintaining them in normal position, a two-step cam carried by each lever, a tens-carry element carried by each lower order registering element for engagement with the first step of said cam to partially release the levers from their stops in passing from "8" to "9," additional means carried by the levers comprising a cam on one side and a stud on the other for wholly releasing the higher order levers from their stops when the lower order lever is released by its tens-carry element passing beyond the second step on said two-step cam, to effect a carry-on-a-carry.

8. Tens-carry mechanism for accumulator apparatus including registering elements of lower and higher order, transfer levers capable of joint reciprocating and pivotal movement, carry pawls carried by said levers, means for imparting movement to the pawls by the rotation of the registering elements, stops for the levers common to all of said levers for maintaining them in normal position, means for imparting movement to the levers relative to their stops, and means for releasing any lever from its stop by the release of the lever of the next lower order.

OLUF L. CLEVEN.
